PERFORMING FIGURE TOY

Albert Cugat, New York, N. Y.

Application March 11, 1949, Serial No. 1,368

Term of patent 14 years

(Cl. D34—15)

To all whom it may concern:

Be it known that I, Albert Cugat, a citizen of the United States, resident of county, city, and State of New York, have invented a new, original, and ornamental Design for a Performing Figure Toy, of which the following is a specification, reference being had to the accompanying drawing, forming part thereof.

The figure is a perspective view of a performing figure toy, showing my new design.

The side not shown is similar to that shown.

I claim:

The ornamental design for a performing figure toy, as shown and described.

ALBERT CUGAT.
